(57) **CLAIM**

The ornamental design for the cup, as shown and described.

DESCRIPTION

FIG. 1 is a top perspective view of the cup according to the present invention;

FIG. 2 is a side view of the cup of FIG. 1, the opposite side being identical;

FIG. 3 is a top view of the cup of FIG. 1;

FIG. 4 is a bottom view of the cup of FIG. 1;

FIG. 5 is a top perspective view of another embodiment the cup of FIG. 1;

FIG. 6 is a side view of the cup of FIG. 5;

FIG. 7 is a top view of the cup of FIG. 5; and,

FIG. 8 is a bottom view of the cup of FIG. 5.

The broken lines in the drawings are for illustrative purposes only and forms no part of the claimed design.
